UNITED STATES PATENT OFFICE.

GIOVANNI CORNARA, OF MANTOVA, ITALY.

EXPLOSIVE CARTRIDGE.

SPECIFICATION forming part of Letters Patent No. 762,229, dated June 7, 1904.

Application filed December 31, 1897. Serial No. 665,052. (No model.)

To all whom it may concern:

Be it known that I, GIOVANNI CORNARA, a subject of the King of Italy, residing at Mantova, Italy, have invented certain new and useful 5 Improvements in Explosive Cartridges, (for which I have obtained patents in Italy, dated December 11, 1896, and in France No. 267,782, June 11, 1897,) of which the following is a specification.

10 The object of this invention is the substitution of products resulting from electrolysis for ordinary explosives. For this purpose I employ a vessel into which I introduce one or more appropriate substances which I submit 15 to the action of an electric current, which decomposes them, giving rise to products capable of recombining to reproduce the original substances or produce new substances, liberating heat and causing an explosion. Ordinarily 20 the substance which I decompose by means of electrolysis is water, which produces a compressed mixture of hydrogen and oxygen, which is one of the most powerful explosives at present known. I employ a reservoir 25 capable of resisting the internal pressures which are produced. I introduce into this vessel an insulated anode having a sufficiently large surface within the same. The walls of the reservoir preferably fulfil the office of a 30 cathode. Water is introduced into the reservoir, filling it either entirely or only partially, and this water contains in solution preferably either caustic potash or soda at five per cent. Although I do not limit my invention to the 35 employment of this electrolyte, (an aqueous solution of an alkali,) I prefer to use it, because I am thereby enabled to construct the reservoir of a metal attackable by acids. The reservoir contents are exploded by means of 40 a cap, a fuse, or a metallic wire rendered incandescent by the passage of an electric current at the desired moment. The anode may also be arranged in such a manner that the electrolytic decomposition of the requisite quantity 45 of water having been effected the anode is left unsubmerged. By the continuance of the passage of the electric current a spark passes between the anode and the cathode and the explosion is produced under the desired con-

ditions. Only one hermetically-closed aperture is necessary in addition to that for the admission of the anode. In order to insure the tightness of the closing of these two apertures, they may both be covered by the water to be decomposed. 50

In the accompanying drawings are represented, by way of example only, some of the arrangements which I usually adopt.

Figure 1 is a section of a reservoir for blasting holes formed in rock of great resistance. 60 Fig. 2 is a section of a reservoir intended to be employed as a projectile torpedo or the like or for introduction into blasting-holes formed in rock of slight resisting power, and Fig. 3 shows a modification. 65

Similar letters of reference designate in all the figures the parts having the same functions.

Referring to Fig. 1, which represents a reservoir for blasting holes formed in rock of great resistance, the rock which it is desired to blow up itself assists the walls of the reservoir, which are relatively thin, to resist the internal pressure which is developed prior to the ignition of the charge. The reservoir is strengthened in the direction of its longitudinal axis by means of a large tension-rod A, provided with a nut B. a indicates the lateral wall of the reservoir, which being in electrical connection with a sheet-iron cylinder c 70 constitutes therewith the cathode of the current for producing the decomposition of the electrolyte in charging the apparatus. b is the terminal of the cathode. d is the terminal of the anode of the same charging-current and is in electrical communication with the internal cylindrical surfaces e e. f f are insulating parts, preferably of ebonite. g g are copper parts serving either as packing for insuring tightness of closing or as contacts 80 for establishing electrical communication. h h represent the terminal of the current causing the ignition of the charge. i i are gas-checks connected with the respective anodes. k is a copper wire which when rendered incandescent causes the ignition of the charge. 90

Referring to Fig. 2, the configuration of the surface e of the anode is obtained by a

copper sheet bent spirally, which owing to its elasticity may be introduced by the opening C.

In the arrangement illustrated in Fig. 3 the explosion takes place immediately the level of the liquid falls below the point s of the anode. The dimensions of the anodes should preferably be calculated in such a manner that the intensity of the charging-current does not exceed seven amperes per square decimeter of surface.

The same current may be employed to charge several reservoirs at once. All that is necessary is to insulate all of them excepting the last to establish communication between the anode of each reservoir and the cathode of the preceding reservoir and to run to earth the last cathode or to connect it to the negative pole of the source of electrical energy.

The elements of the electrical action (resistance, intensity, electromotive force) undergo no variation during the decomposition of the water in the closed vessels. The duration of the electrolytic action and the data, which are known with regard to the current supplied to the apparatus, the superficies of the anode and of the cathode, and with regard to the quantity and the nature of the electrolyte enable a computation of the quantity of the gases produced and of the explosive force stored within the reservoir.

The advantages resulting from the employment of electrochemical reservoirs are, among others, the following: an enormous explosive force, the possibility of utilizing the motive force available in mines and even at times when it cannot be used for other purposes, the absence of all danger to the workmen, the harmlessness of the products of explosion, and, finally, the low cost.

What I claim as my invention is—

1. In an explosive cartridge, an electrolytic cell having metallic walls, said metallic walls forming a cathode, an alkaline solution within said cell, an anode extending in said cell and free of the cathode and adapted in connection

with the cathode to electrolyze said solution, and means extending in a cathode for exploding said electrolytic decomposition.

2. In an electrical cartridge, a metallic cell forming a cathode, an alkaline solution within said cathode, an anode extending in the cathode and in connection therewith adapted to electrolyze said solution thereby forming an explosive mixture, and a metallic wire extending in said cell and adapted to be rendered incandescent for exploding said mixture, substantially as described.

3. In an explosive cartridge, an electrolytic cell having metallic walls forming a cathode, an alkaline solution within the said cell, an anode extending in said cell, and free of said cathode and adapted in connection with the cathode to electrolyze said solution forming thereby an explosive mixture, said anode having as great a cross-section as possible, and means extending in the cathode for exploding said electrolytic decomposition.

4. In an explosive cartridge, an electrolytic cell forming a cathode, an alkaline solution within said cathode, an anode extending in and free of the cathode and adapted in connection with the cathode to electrolyze said solution forming thereby an explosive mixture, a gas-check connected with the anode, and means extending in the cathode for exploding said mixture.

5. In an explosive cartridge, an electrolytic cell having metallic walls forming a cathode, an alkaline solution within said cell, an anode extending in said cell and free of the cathode and adapted in connection with the cathode to electrolyze said solution, a gas-check connected to the anode, and a metallic wire extending in said cell and rendered incandescent for exploding the electrolytic decomposition.

In testimony whereof I have hereunto set my hand in presence of two subscribing witnesses.

GIOVANNI CORNARA.
